UNITED STATES PATENT OFFICE.

ABRAHAM R. MANN, JR., OF WEISEL, PENNSYLVANIA.

CIGAR-LIGHTER.

1,025,001.

Specification of Letters Patent.

Patented Apr. 30, 1912.

Application filed November 26, 1910. Serial No. 594,287.

To all whom it may concern:

Be it known that I, ABRAHAM R. MANN, Jr., a citizen of the United States, and residing at Weisel, in the county of Bucks and 5 State of Pennsylvania, have invented certain new and useful Improvements in Cigar-Lighters, of which the following is a specification.

My invention relates to improvements in 10 cigar-lighters, more particularly that type wherein the same, in the form of what may be termed a cartridge or torch, is fixed to the cigar.

The invention has for its object to provide 15 a device of the character indicated which will insure the lighting of the cigar, also to effect such lighting the instant the lighted match or rather its flame, is presented to the cigar; also whereby the possibility of 20 the transmission of any fumes to the mouth from the lighting of the cigar by a match is prevented or obviated.

The invention consists of the instrument- 25 alities or features substantially as herein- after fully disclosed and defined by the claim.

In the accompanying drawing, illustrating 30 the preferred embodiment of my invention wherein, it will be understood that changes or modifications pertaining to the details thereof may be made without departing from the spirit of the invention,—Figure 1, is a perspective view of a cigar with my invention applied thereto. Fig. 2, is an enlarged detailed longitudinal section of the 35 same, the cigar being fragmentary. Fig. 3, is a transverse section of the invention.

In practising my invention, I take an 40 ordinary cigar, designated by the reference character 1, and apply to the relatively outer end thereof, a tubular paper or other like fibrous member 2, the major portion of said

paper or fibrous member or sleeve being suitably fixed, as by paste, to the cigar. The remaining portion of said member extends 45 beyond the end of the cigar, forming a hollow cylindrical shell-like extension to the cigar, which extension has suitably applied to and around its free edge or end, in outstanding ring or annular outline, an explosive fuse or readily ignitable composition 3, such, for instance, as usually employed in forming match-heads, and which, as will be readily appreciated, is readily fixed by the presentation thereto of the flame of a lighted 50 match, as usually practised in lighting a cigar. The paper shell thus formed is also suitably saturated with an inflammable oil for aiding its action in effecting the lighting of the cigar, also for the ready and complete destruction of said paper-shell. A cigar thus equipped may be readily lighted, without any of the usual inconveniences or annoyances of repeated striking and lighting of matches before effecting the lighting 55 of the cigar, thus initially insuring the lighting operation, as doubtless will be appreciated from the foregoing.

Having thus described my said invention, what I claim as new and desire to secure by 70 United States Letters Patent, is:—

A lighting attachment for cigars consisting of an inflammable tube one end of which is adapted to receive and be fitted to the lighting end of a cigar, and the other end of which is provided with a readily ignitable fuse in the form of a bead encircling the tube. 75

In testimony whereof I affix my signature in presence of two witnesses.

ABRAHAM R. MANN, JR.
